Primary Examiner — W. A. Teddy Falloway*(74) Attorney, Agent, or Firm* — Oblon, McClelland, Maier & Neustadt, L.L.P.(57) **CLAIM**

The ornamental design for a packaging case, as shown and described.

DESCRIPTION

FIG. 1 is a top plan view of a packaging case;
 FIG. 2 is a bottom plan view thereof;
 FIG. 3 is a front elevational view thereof;
 FIG. 4 is a rear elevational view thereof;
 FIG. 5 is a right side elevational view thereof;
 FIG. 6 is a left side elevational view thereof;
 FIG. 7 is a front, top, and left side perspective view thereof;
 FIG. 8 is a front, bottom, and right side perspective view thereof;
 FIG. 9 is a front, top, and left side perspective view thereof in a usage condition containing syringes;
 FIG. 10 is a cross-sectional view taken along line 10-10 in FIG. 1;
 FIG. 11 is a cross-sectional view taken along line 11-11 in FIG. 1;
 FIG. 12 is a cross-sectional view taken along line 12-12 in FIG. 1;
 FIG. 13 is a cross-sectional view taken along line 13-13 in FIG. 1; and,
 FIG. 14 is a cross-sectional view taken along line 14-14 in FIG. 1.

The broken lines in FIG. 9 illustrate environmental subject matter that forms no part of the claimed design.
